UNITED STATES PATENT OFFICE

2,541,690

RADIO TIME SWITCH

Joseph C. Dabkowski, New Britain, Conn.

Application December 15, 1947, Serial No. 791,723

3 Claims. (Cl. 161—1)

1

This invention relates to radio time switches, and more particularly to a switch for automatically interrupting the supply of power to a radio or other electrical appliance at the end of a predetermined period of time.

One object of this invention is to provide a device of the above nature, wherein a timing mechanism will overbalance a weighted operating member at the end of the predetermined time period for actuating the circuit-breaking means.

Another object is to provide a device of the above nature in which the weighted operating member will function by virtue of its balance, whereby the use of latches will be avoided.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawings,

Fig. 1 is a front elevation of the radio time switch, partly in section, showing the cabinet doors in open position.

Fig. 2 is a front sectional view, on an enlarged scale, showing the weighted operating member, the reset rod, and a portion of the timing mechanism.

Fig. 3 is a side view of a portion of the rotating pointer arm taken on the line 3—3 of Fig. 2.

Referring now to the drawing in which like reference numerals denote corresponding parts throughout the several views, the numeral 10 indicates generally a cabinet having a bottom wall 11, vertical side walls 12, 13, which are extended downwardly in order to support the bottom wall 11 in elevated position, and a horizontal top wall 14. The cabinet 10 is also provided with a pair of swingable doors 15, 16, whereby the front of the cabinet may be closed after the device has been set in operation.

The side wall 13 is provided with an aperture 17 (Fig. 1) which supports an electric outlet receptacle 18 of conventional type. The receptacle 18 will serve as a means for connecting the power supply cord of the radio or other electrical appliance which is to be controlled. Power is furnished to the receptacle 18 by means of a cord 19 which will receive power from any suitable source. The cord 19 enters the cabinet 10 through a bushing 20 in the bottom wall 11, and is connected to

2

the receptacle 18 by means of conductors 21, 22, 23, and a circuit-breaking means 24 in series with the receptacle 18.

The circuit-breaking means 24, such as a "microswitch," is provided with an upstanding actuating lever 25 which will break the electric circuit when it is moved toward the left (as seen in Fig. 1). The lever 25 will be operated by means including a spring-driven timing mechanism 26 having a manually settable pointer arm 27 which will be rotated at a constant speed over a graduated dial 28 mounted on the front surface of the timing device. The dial 28 may be graduated in seconds, minutes, or hours, as desired.

16 The outer end of the arm 27 has a pointer 29 which serves as an index on the dial 28, and an outstanding lug 30 which is adapted to engage an upstanding finger 31 at the end of an upper arm 32a of a bell-crank trip lever 32. The trip lever 32 is carried for lateral swinging movement over the upper end of a vertical bracket 33 mounted on the bottom wall 11, and includes a lower arm in the form of a threaded rod 34. The threaded rod 34 has an angular end portion 35 secured to the upper arm 32a of the lever 32 as by soldering or welding, and carries a knurled thumb nut 36 which serves as an adjustable weight, whereby the center of gravity or balance point of the bell crank lever 32 may be adjusted.

20 The upper arm 32a of the trip lever 32 is connected to the actuating lever 25 of the circuit breaking means 24 by means of a cord 37 of such a length that it will be in a slack condition when the trip lever 32 is set in position for engagement by the lug 30, as shown in Fig. 1.

The length of the cord 37 will be so adjusted that the cord will be brought into taut condition after the pointer arm 27 has swung the trip lever 40 32 sufficiently toward the left to carry its center of gravity beyond the balance point.

The movement of the trip lever 32 will be limited by the engagement of the threaded rod 34 with an upper abutment 38 and a lower abutment 45 which are provided by the ends of a vertical slot 40 formed in the upper portion of a vertical reset rod 41. The rod 41 is reciprocable in an aperture 42 in the bottom wall 11 of the cabinet, but is normally held stationary by means of an integral intermediate flange 43 which is held against the upper surface of the bottom wall 11 by a coiled spring 44 engaged between the lower surface of the wall 11 and a handle 45 on the lower end of said rod.

Operation

In operation, the timing mechanism 26 will first be wound up and the cord 19 connected to a suitable source of electric current.

The radio or other appliance which is to be controlled will then be plugged into the electric receptacle 18. The pointer arm 27 of the timing mechanism 26 will then be moved counterclockwise manually in order to provide a desired time period as indicated by the dial 28, during which electric current will be supplied to the receptacle 18.

The timing mechanism 26 will then operate to swing the arm 27 clockwise at a constant rate of speed, and eventually the lug 30 will engage the finger 31 to overturn the trip lever 32. During the first part of the movement of the lever 32, the slack of the cord 37 will be taken up, and during this interval, no force will be exerted upon the actuating lever 25 of the circuit-breaking means 24. However, as soon as the lever 32 has become overbalanced it will move rapidly to the left, whereupon the slack of the cord 37 will be suddenly taken up, and the actuating arm 25 moved toward the left to break the circuit through the receptacle 18, thereby turning off the radio or other appliance.

If it is found that the bell crank trip lever 32 is not overbalanced at the proper point to produce the most efficient operation, the thumb nut 38 may be adjusted in order to shift its center of gravity.

When it is desired to place the radio or other appliance in operation again, the reset handle 45 will be pressed upwardly so that the abutment 39 will move the threaded rod 34 upwardly and thereby restore the trip lever 32 to its operative position, as shown in Fig. 2.

This operation will also restore the slack in the cord 37, and will permit the actuating arm 25 to move toward the right, thereby reestablishing the electrical connection to the outlet 18.

It will be noted that the proper set position of the trip lever 32 will be determined by the engagement of the upper abutment 38 of the reset rod 41 with the threaded rod 34. Thus, the finger 31 will lie in the path of the lug 30, so that the arm 27 may actuate the circuit-breaking means after the desired interval.

While there has been disclosed in this specification one form in which the invention may be embodied, it is to be understood that this form is shown for the purpose of illustration only, and that the invention is not to be limited to the specific disclosure, but may be modified and em-

bodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a radio time switch, the combination comprising a horizontal base support, a bracket upstanding therefrom and having a horizontal pivot, a bell crank operating trip member swingable on said pivot, a horizontally extending arm fixed to a lower portion of said trip member, a reset rod provided with a vertical through slot slidably mounted in said base support, said horizontally extending arm extending through said vertical slot, the center of gravity of said trip member being located above said pivot at all times and being capable of lying selectively on either side thereof, the ends of said slot being operative to limit the extent of passage of said trip member over said pivot, a circuit-breaking device, means to loosely link said trip member to said circuit-breaking device, and a timing mechanism comprising a rotating arm driven at a constant speed adapted to engage directly with and overturn said trip member, whereby the weight of said trip member will operate said circuit-breaking means.
2. The invention as defined in claim 1 wherein said slidably mounted reset rod is provided with manually operable means to turn said trip member to inoperative position.
3. The invention as defined in claim 1 wherein said slidably mounted reset rod is provided with spring actuated means to hold said reset rod at one position, and also to allow selective manual sliding thereof to a second position, said sliding being operative to return said trip member to inoperative position.
